No. 682,136.

Patented Sept. 3, 1901.

G. B. DONNELLY.
CLAMP FOR RAILWAY FROGS.

(Application filed Dec. 6, 1900.)

(No Model.)

UNITED STATES PATENT OFFICE.

GEORGE B. DONNELLY, OF CHICAGO, ILLINOIS, ASSIGNOR OF ONE HALF TO
THOMAS J. PEDEN, OF SAME PLACE.

CLAMP FOR RAILWAY-FROGS.

SPECIFICATION forming part of Letters Patent No. 682,136, dated September 3, 1901.

Application filed December 6, 1900. Serial No. 38,889. (No model.)

To all whom it may concern:

Be it known that I, GEORGE B. DONNELLY, a citizen of the United States of America, and a resident of Chicago, in the county of Cook 5 and State of Illinois, have invented certain new and useful Improvements in Clamps for Railway-Frogs, of which the following is a specification.

My invention relates particularly to the 10 clamping mechanism used in retaining in proper position the wing-rails or guard-rails of a railway-frog.

The main objects of my invention are to provide improved clamping mechanism designed to withstand the strain on the rails 15 and to make such mechanism readily adjustable and to some extent self-adjustable to compensate for ordinary wear on the clamping parts.

20 The further objects of the different parts with which I put my invention into practice will be understood from the following description, with reference to the accompanying drawings, in which—

25 Figure 1 is a top plan of a railway-frog and clamping mechanism constructed according to my invention. Fig. 2 is a side elevation of same. Fig. 3 is a vertical section on the line 3 3 of Fig. 1. Fig. 4 is a vertical section 30 on the line 4 4 of Fig. 2. Fig. 5 is an enlarged horizontal section of one of the brackets for adjustment to the side of the rail, showing the nut-lock and spring therein. Fig. 6 is a top plan of the auxiliary jaw used in connection 35 with the clamp.

In the device shown in the drawings the wing-rails 1 and main rails 2 are riveted to the tie-plates 5. The wing-rails are connected by the clamps 6 and 7. Each of said clamps 40 has a jaw 8 with an aperture therein for receiving the pin 9, which passes through suitable apertures in the rails. Each of said clamps has an opposite jaw 10, which has an auxiliary jaw or block 11, seated inwardly of 45 same. The jaw 10 rests in a recess 12 in the block 11. Said block is provided with wings 13 and 14, which have their free ends projecting toward the base-flange 15 of the adjoining wing-rail. An opposite block 16 rests 50 against said wing-rail and has an aperture

17 therein for receiving one end of the pin 9. The wings 13 and 14 extend on each side of the block 16 and under the wedge. The blocks 11 and 16 are grooved on their inner faces for receiving the wedge 18. Said wedge 55 is provided with a threaded shank 19, which passes through an aperture in the bracket 20. The bracket 20 has a chamber or pocket 21 in the side toward the free end of the shank 19. A nut 22 is threaded upon the free end 60 of said shank and has the sleeve 23 pressed toward said nut by the spring 24, which is seated in the pocket 21. The sleeve 23 is provided with a key 25, which is slidable in the keyway 26 of the bracket 20. At the free 65 end of the wing-rail on the side toward the wedge 18 a bracket 27 supports the threaded shank 19 and has an extension 28 on the inside of the rail. Said extension is slotted to receive the foot-guard 29. The opposite wing-rail has a bracket 30 bolted to the rail and which is also slotted to receive the foot-guard 70 31. Blocks 32 and 33 are seated between the wing-rails at each of the clamps.

The operation of my device is as follows: 75 The pin 9 is first passed through the rails in the position shown in Figs. 1 and 3. The clamp 6 is then placed in proper relative position, with the pin extending into the aperture in the jaw 8. The block 11 is then 80 placed in proper position inward of the jaw 10, and the block 16 is afterward inserted, with the pin 9 projecting into its aperture. The operator will now pass the wedge 18 between the blocks 11 and 16 and through the 85 bracket 20, spring 26, and sleeve 23. The nut 22 will now be screwed upon the free end of the shank 19. To tighten the nut, the operator will press the sleeve 20 inwardly against the spring and then turn the nut 22 until 90 same is locked by the lug 34, which projects into a suitable recess in said nut. It will be seen that if the blocks 11 and 16, the jaw 10, or the wedge 18 is jammed through a strain 95 on the wing-rails, so as to loosen the wedge 18 in its seat, the latter will be drawn toward the bracket 20 through the action of the spring 24. This will again tighten the clamp. The block 11 relieves the strain on the jaw 10 and avoids the danger of breakage of said 100

jaw. The pin 9 serves to hold the clamping parts against sliding movement longitudinally of the wing-rails.

It will be understood that various details of 5 the device shown may be altered without departing from the spirit of my invention. I therefore do not confine myself to such details except as hereinafter limited in the claims.

10. What I claim as my invention, and desire to secure by Letters Patent, is—

1. The combination of a pair of diverging rails; a clamp connecting said rails; a wedge acting between one of the rails and the clamp-jaw; a spring normally tightening said wedge in its seat; and means for adjustably locking said wedge between said rail and clamp-jaw. 15

2. The combination of a pair of diverging rails; a clamp connecting said rails; said 20 clamp being secured against movement longitudinally of said rails; a wedge acting between one of the rails and the clamp-jaw; a spring normally tightening said wedge in its seat; and means for adjustably locking said 25 wedge between said rail and clamp-jaw.

3. The combination of a pair of diverging rails; a clamp connecting said rails; a block 30 removably seated between one of the rails and its clamp-jaw and having a seat for said clamp-jaw; and a wedge acting between said block and the adjoining rail and thereby urging the block against said clamp-jaw.

4. The combination of a pair of diverging rails; a clamp connecting said rails; said 35 clamp being secured against movement longitudinally of said rails; a wedge acting between one of the rails and the clamp-jaw and having a threaded shank; an apertured member secured to said rail and having the threaded shank passing through the aperture; and a nut 40

on said shank, acting toward said member and whereby the wedge may be adjusted between said rail and clamp-jaw; and a spring acting between said nut and apertured member for tightening said wedge. 45

5. The combination of a pair of diverging rails; a clamp connecting said rails and having one of its jaws secured against movement longitudinally of said rails; a block secured against movement longitudinally of said rails 50 between the other jaw and its rail; a wedge acting between such jaw and said block; means for adjustably locking said wedge between such jaw and block; and a spring normally tightening said wedge in its seat. 55

6. The combination of a pair of diverging rails; a clamp connecting said rails and having one of its jaws secured against movement longitudinally of said rails; a block secured against movement longitudinally of said rails 60 between the other jaw and its rail; a second block engaged by and removably seated inward of said other jaw; a wedge acting between said blocks; and means for adjustably locking the wedge between said blocks. 65

7. The combination of a pair of diverging rails; a clamp connecting said rails; a block removably seated between one of the rails and its clamp-jaw and having a seat for said clamp-jaw; a wedge acting between said block and the adjoining rail and thereby urging the block against said clamp-jaw; and a spring normally tightening said wedge between the block and said adjoining rail. 70

Signed at Chicago this 1st day of December, 1900. 75

GEORGE B. DONNELLY.
